UNITED STATES PATENT OFFICE.

ALEC J. GERRARD AND PARVIN WRIGHT, OF CHICAGO, ILLINOIS.

WIRE-TYING MACHINE.

Application filed November 29, 1920. Serial No. 427,101.

To all whom it may concern:

Be it known that we, ALEC J. GERRARD and PARVIN WRIGHT, respectively a subject of the King of Great Britain and a citizen of the United States, each residing at Chicago, in the county of Cook and State of Illinois, have invented certain new and useful Improvements in Wire-Tying Machines; and we do hereby declare the following to be a full, clear, and exact description of the invention, such as will enable others skilled in the art to which it appertains to make and use the same.

This invention relates to wire twisting machines and has for its object to provide an apparatus of this nature especially adapted for wiring bundles, boxes, etc., which will be simple in construction, comparatively inexpensive to manufacture, and more efficient in operation than those which have been heretofore proposed.

With these and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

Figure 1 is an end elevational view of a machine made in accordance with this invention;

Figure 2 is a side elevational view of the parts shown in Figure 1;

Figure 3 is an enlarged partially sectional view of the operating wheel and its associated parts;

Figure 4 is a sectional view taken on the line 4—4 of Figure 3, looking in the direction of the arrows;

Figure 5 is a view of the parts shown in Figure 3, but looking in an opposite direction;

Figure 6 is a plan view of the reel for holding the wire;

Figure 7 is a sectional view taken on the line 7—7 of Figure 6;

Figure 8 is a view partially broken away, of the motor and gear train operating the twisting mechanism;

Figure 9 is a sectional view of a portion of the parts shown in Figure 8;

Figure 10 is an enlarged detail view of the wire, the driving shaft, the wire twisting gear train, and its associated parts;

Figure 11 is an enlarged sectional view of the wire tensioning friction clutch;

Figure 12 is an enlarged perspective view of a modified form of friction clutch;

Figure 13 is a sectional view of a somewhat modified form of clutch, shown in Figure 12; and

Figure 14 is a view of the knot tied by this machine.

1 indicates any suitable supporting base; 2 a standard rising therefrom, provided with the holes 3 into which fit a supporting pin 4 on which rests the sleeve 5, carrying the arm 6 provided with the bundle supporting plate 7. Slidably connected with the standard 2 is the frame 8 carrying the twisting mechanism, as will be presently described. Rising from said frame 8 is the guiding member 9 passing through the sleeve 10 rigid with the arm 11, carried by the head 12, which latter is also rigid with said standard 2.

The extreme top of the standard 2 is provided with the circular plate 13, through which passes the power shaft 14, rigidly attached to the member 15 as by the key 16, see Figure 4, and loosely mounted on said shaft 14 is the clutch operating wheel 17, as shown. Said wheel 17 is provided with a plurality of spokes 18 each of which is provided with a hole 19, as best shown in Figures 3 and 4. Passing through one of the holes 19 is a pin 20 rigid with the arm 21, having a right-angular extension 22 passing through a hole 23 in the member 15, and provided with the cam 24, as shown.

Carried by the stationary member 15 and pivoted thereto as at 25 and 26 respectively, are the pawls 27 and 28, controlled by the springs 29, and the lower ends 30 of which take against the curved surfaces 31 of the stationary member 13, as will be readily understood.

The wheel 17 being loosely mounted on the shaft 14, and connected to the member 15 which is rigidly mounted thereon, as just disclosed, it is evident that if said wheel be turned in a clockwise direction, as indicated by the arrow in Figure 3, it will move idly through a considerable angle, or, say, through 90° during which time it will have acquired considerable momentum before the strain will be brought on the pin 20 and the members 21 and 22 to pull the member 15 bodily around with the wheel. After this idle arc of, say, 90° has been reached, any

further motion of the wheel 17 will, through the said members 20, 21, and 22, pull the said member 15 around with said wheel and this said motion will cause the shaft 14 to rotate during the rest of the movement of said wheel 17. The rotation of the shaft 14 will turn the pinion 32 carried by said shaft, see Figure 2, and the rotation of said pinion will move downwardly the rack 33, with which said guide member 9 is provided. The downward movement of the rack 33 and guide member 9 carries with it the frame 8 and the lower flat surface 34 of said frame, which takes against the top 35 of the package 36 to be wired. In other words, from the construction just described, it is evident that the rotation of the wheel 17 in the proper direction will lower the surface 34 of the frame 8 onto the top 35 of the package while the bottom 37 of said package is resting upon the platform 7, and thus will the package 36 be squeezed between said surface 34 and said platform 7 in a manner which will be readily understood. It is further evident that as the pawls 27 and 28 are thus carried around the surface 31 of the disk 13 they will move idly over said surface, and especially since the cam 24 will be so turned on the extension 22 as a center, as to separate the pawl 27 from said surface 31, and thus prevent it taking against said surface 31. On the other hand, when power is released from the wheel 17 the natural tendency of the package 36 to expand will tend to reverse the motion of said shaft 14 and to thus release the pressure. However, when this occurs, the lower end 30 of the pawl 28 will bite against the surface 31 and prevent any backward movement. It thus results that the package 36 is held firmly under compression.

In order to conveniently operate the wheel 17 and also to store up a considerable momentum therein during the compressing operation, I provide on the standard 2 a sleeve 40 provided with an arm 41 which carries a sleeve 42 in which is mounted a short shaft 43 on which is pivoted as at 44 a lever 45 which is provided with a foot treadle 46, as best shown in Figures 1 and 2. Connected to said lever 45 as at 48 is a wire rod or chain 49 which passes upwardly and over the hub 50 of said wheel 17, as is plainly shown in Figures 1 and 5, and is further connected to a pin 51 which is adjustable in one of the holes 52 with which said hub 50 is provided.

Also connected to said pin 51 is a continuation 53 of said wire or connection 49, and connected by one end to said member 53 is a coil spring 54 the other end of which is connected with a similar member 55 leading back to the foot treadle 46 and the lower end of which is joined to the base 1 as at 56. It thus results that a sharp or sudden push on

the foot treadle 46 will cause said wheel 17 to rapidly revolve, and thus stretch the spring 54, so as to store up power therein. On the other hand, as soon as the pressure is relieved from the foot treadle 46, the spring 54 will react and turn the wheel rapidly in the opposite direction. In other words, a little consideration will show that if power is suddenly applied by the foot to the member 46 the wheel 17 will be turned in a clockwise direction, as seen in Figure 5 or in a counter-clockwise direction, as seen in Figure 2. The turning of said wheel in a counter-clockwise direction will turn the cam 24 toward the left, as seen in Figure 3, will forcibly remove the dog 28 from the surface 31 and thus will permit the guide 9 and the frame 8 to rise, thus freeing the package 36, so that, so long as the foot is retained on the member 46 said member 9 will be held in its uppermost position. On the other hand, when the foot is released, from the member 46, the spring 54 will re-act to lower the said member 9 and frame 8 in the manner above disclosed. Of course, should it be desired to cause the compressing action to take place upon the depression of the member 46, instead of upon the release of said member, it is only necessary to interchange the connections 49 and 55 with the lever 45, so that said lever will pull down on the connection 55 instead of on the connection 49. It is an important feature of this invention, as will appear below, that a considerable momentum is stored up in the wheel 17 before the compression action takes place, for this said momentum is utilized to impart a maximum compression of the bundle 36 with the expenditure of a minimum of power.

Referring more especially to Figure 8, 60 represents any suitable electric motor provided with a drive shaft 61 carrying a worm 62 meshing with the worm gear 63 rigid on the main driving shaft 64 carrying the driving member 65 and surrounded by the coil spring 67, the compression of which is adjusted by the nuts 68 working on the screw threads 69, with which said shaft 64 is provided.

Mounted on said shaft 64 is the sleeve 70 carrying a tooth ring like member 71 and a clutch member 72, all as will be clear from Figure 9. Also mounted on said shaft 64 is the sleeve 73 carrying a clutch member 74 with which the sleeve 75 is rigidly connected and rigid with said sleeve 73 is the worm 76 meshing in the worm gear 77. Said sleeve 73 also carries an enlargement 78 against which one end of the spring 67 abuts, as is plainly shown in Figure 10.

Rigid with said sleeve 70 is the driving pinion 80 meshing with the main driving gear 81 meshing with the slotted twisting pinion 82 provided with the slot 83 all as will be clear from Figures 8, 9 and 10 of the

drawings. In other words, power being imparted to the motor shaft 61, the worm gear 63 will be turned, which will rotate the main driving member 65, rigid therewith, and 5 said member 65 will rotate the clutch member 74, or the clutch member 72 according to which may be engaged with said driving member 65. If the clutch member 72 should be engaged with said member 65, then the 10 sleeve 70 will be driven by said member 65 and shaft 64 and the driving of said sleeve 70 will turn the driving pinion 80, the main twisting gear 81, and the twisting pinion 82. On the other hand, if the clutch member 15 74 should be engaged with said driving member 65 as is indicated in Figure 9, then the sleeve 73, worm 76, and worm gear 77 will be driven by said motor 60 and motor shaft 64, all as will be clear from the drawings. 20 Mounted in a portion 85 of the frame 8 is a wire holding post 86 located on one side of the twisting pinion 82, while mounted in another portion 87 of said frame 8 is another wire holding post 88 located on the 25 other side of said twisting pinion 82. Surrounding the post 88 is a cutter 89 in all respects similar to the cutter illustrated in our copending application #391,678, filed June 25, 1920, and entitled Automatic wire 30 tensioning and tying machine.

Briefly, this said cutter 89 is operated through the lever 90 indicated in dotted lines in Figure 10, which lever is operated through a connection, such as 900 with the 35 main driving gear 81, all as is disclosed in said copending application. 91 represents an enlargement or partial housing for the worm gear 77 and its associated parts. As is best illustrated in Figure 11, one face of 40 the worm gear 77 is hollowed out as at 92 and a portion thereof is inclined as at 93 and is provided with a friction material 94, which may extend substantially throughout the hollowed space, as indicated, and against 45 which fits a friction disk 95. Said disk is held in place by means of the nut 97 fitting on the hub 98 of the worm gear 77, and the outer periphery of said disk 95 is curved as at 99 for a purpose presently to be described. 50 A short shaft or bolt 100 passes through the hub 98 of the worm gear 77 and is provided with a nut 101 which takes against the enlargement or housing 91 of the frame work 8, all as is plainly shown in 55 Figure 11.

Loosely mounted on said bolt or shaft 100 is the companion disk 102 provided with a curved periphery 103. Fitting under the head 104 of the bolt 100 and taking against the outer surface of the disk 102 is the spring 105 which governs the distance between the surfaces 99 and 103 when a wire is wedged between said surfaces, all as will presently appear. In other words, it will be seen below that the surfaces 99 and 103 con-

stitute a gripping means by which a bight of the wire may be readily gripped and a tension placed thereon when the worm gear 77 is rotated. Mounted on the shaft 43 see Figures 1 and 2, is a reel 108 for holding 70 a coil of wire 109. Said reel comprises a bottom supporting means 110 on which rests said coil of wire 109; and a top plate member 111 provided with downwardly depending holding members 112 fitting inside said 75 coil 109.

Immediately under the top member 111 is a second member 113 provided with downwardly depending feet 114, which alternate with the holding members 112 and 80 also extend on the inside of the coil of wire, so that the latter is firmly held in place. Said supporting members 110 are rigid with the rotatable hub like member 115, mounted on the sleeve 116 held in place by the member 42, as above described; located to one side of the plate 111 and rotatable around the periphery thereof is the tube member 120.

Said tube member 120 is provided with the universal joint 121 see Figures 1 and 2, 90 so that it may freely swing around said member 111 to uncoil the wire, while the wire 122 passes up through said revolving tube 120 and into the goose neck shaped tube 123 secured to the head 12, as at 124, all as 95 will be clear from the drawings.

It thus results from this construction that a wire such as 122 may be readily unwound from a coil 109, and carried by the tubes 120 and 123, to a point 124 in close proximity 100 to the twisting pinion mechanism, as will be readily understood.

The operation of this machine is as follows:

The platform 7 having been suitably adjusted along the standard 2, it is clamped in place by the pin 4, whereupon a box 36 or other package to be wired is placed upon said platform, whereupon the foot pedal 46 which has been previously depressed in 105 order to maintain the surface 34 of the frame 8 above said box 36, may now be released. The releasing of the foot pedal 46 will permit the spring 54, which was previously under tension, to now rotate the wheel 17 in a clockwise direction as seen in Figure 3, and this rotation will cause the pinion 32 to move the rack 33 and frame 8 downwardly, so that the surface 34 will contact with the top 35 of the package 36. 115

Owing to the lost motion of the wheel 17 due to the peculiar connection between the same and the shaft 14, said wheel will have gained a considerable momentum before the pinion 32 is actuated and therefore this momentum will be used up in compressing the package in the manner above disclosed. The package having been thus put under compression, the pawl 28 will automatically 125 take against the surface 31 of the disk 13 130

and prevent said compression from being released.

An end 130 of the wire 122 may now be suitably attached to the holding post 86, whereupon its bight 132 may be passed in a clockwise direction, as seen in Figure 10, through the slots 131, through the slot 83 of the twisting pinion 82, through the slot 133 on the right hand side of said pinion 83, through the slot of the holding post 88, and around the package 36 and back to the holding post 86, whereupon what now becomes the bight 134 of said wire is again passed through the slots 131, 83, and post 88 in parallel relation, all as will be clear from Figures 8 and 10.

From the post 88 the said bight 134 passes into the space between the curved surfaces 99 and 103, as best shown in Figure 11, and becomes wedged there, so that the turning of the disks 95 and 102 by means of the friction material 94, will cause said bight 134 to be put under tension. The amount of friction that exists between the clutch member 95 and the surface of the worm gear 77 is regulated by the nut 97, while the gripping action between the surfaces 99 and 103 is regulated by the spring 105, all as will be clear from Figure 11.

30 The motor 60 continuing to run, and the worm 76 continuing to turn the worm gear 77, there will come a time when the clutch member 95 will slip over the surface of the gear 77, and thus will the increase of tension on the wire cease. In other words, the nut 97, see Figure 11, will determine the amount of tension which is automatically put into the bight 134 of the wire through the continuous action of the motor 60 and worm 76.

When the maximum tension of the wire due to this said slipping action of the clutch member 95 occurs, the worm 76 will automatically move toward the right, as seen in Figure 10, on the worm gear 77 as a guide, and against the compression of the spring 67. Again the adjustment of the nut 68 will determine this lateral movement of the worm 76, and also the tension that is to be put upon the bight 134. The movement of the worm 76 toward the right, as just stated, will carry with it the sleeve 74, the sleeve 75 rigid with said sleeve 74, and the depending annular lug or ring 135, see Figure 9, which takes against the circular shoulder with which the clutch member 72 is provided.

In other words, when the worm 76 thus moves against the compression of the spring 67, it disengages the tooth 136 of the clutch member or sleeve 74 from the tooth 137 of the driving member 65, and causes the tooth 138 of said driving member to engage one of the teeth of the clutch member 72. Of course, if nothing else were provided to pre-

vent it, the spring 67 being under compression would immediately force the tooth 136 toward the left, as seen in Figures 9 and 10, and thus after a complete rotation of the tooth 137 it would automatically reengage 70 said tooth 136.

In order to prevent this, the ring shaped member 160 is secured to the frame 8 as shown at 161, and is provided with the cam surface 162 against which takes the cam surface 163 of the member 71 which is rigid with the sleeve 70. The engagement of said surfaces 162 and 163 and the rotation of the member 71 is compelled by means of the fact that as soon as the tooth 136 leaves the tooth 137 the tooth 138 will engage one of the teeth such as 164 of the clutch member 72 and thus compel the said member 71 to rotate relatively to the said member 160.

It thus happens that the cam surfaces 162 and 163 force a tooth such as 164 well over toward the right, as seen in Figure 9 and into engagement with the driving tooth 138 of the member 65, and the flat surface 166 of the member 160 will hold the parts in position, as just stated, until a complete rotation is had, during which the twisting operation is accomplished.

That is to say, the engagement of said driving member 65 with the clutch member 72 in the manner just stated will cause the continuously rotating shaft 64 to turn the sleeve 70, the driving pinion 80, the twisting gear 81 and the twisting pinion 82, which latter will twist together the bights 132 and 134 of the wire 122, all as will be clear from Figures 8, 9, and 10. The knot thus produced by the action described is illustrated in Figure 14.

It is very desirable in machines of this kind to be able to readily disengage the twisted wire from the slot 83 of the twisting pinion, and in order to do this, said slot 83 must accurately register with the slot 133 of the frame, see Figure 8. But when the bights 132 and 134 are thus twisted together, their natural tendency is to untwist and to thus reverse through a small angle the motion of the said pinion 83, which tends to bring the slot 83 out of register with the slot 133.

In order to void this tendency, it is important that the wire bights 132 and 134 should be overtwisted, so that when it untwists, it will just bring the slots 83 and 133 into register. This overtwisting of the said bights is accomplished by providing the member 71, Figure 9, with the hook shaped tooth 170 which fits into a corresponding depression in the member 160. But when the member 71 is rotated in the manner above disclosed, the said hook like tooth 170 passes beyond its normal position before it can snap back into its companion slot, and this excessive movement puts in the extra twist above mentioned.

It thus happens that a reverse motion of the pinion 82 will carry the hook 170 back into its normal position, shown in Figure 9. The snapping back of the tooth 170 in the 5 manner disclosed is rendered possible by reason of the fact that the clutch member 72 is at that time disengaged from the tooth 138, and therefore the twisting mechanism is not subject to the power of the shaft 64.

10 Immediately after the twisting operation has been completed, the roller member 900, Figure 10, with which the gear 81 is provided, strikes the end of the lever 90, see dotted lines in Figure 10 and operates the 15 cutter 89 to sever the said bight 134, and thus to leave the wire 122 ready for another operation.

It will thus be seen that a continuous operation of the motor 60 first puts the wire 20 under a predetermined tension, determined by the power of the spring 67 and its adjustment, and also determined by the friction between the clutch member 95 and the surface of the worm gear 77.

25 Owing to the fact that the wheel 17 is of a considerable weight and owing to the further fact that a considerable amount of power is stored up therein before the compressive action on the package 36 takes 30 place, an operator can, with relatively light effort, put the package 36 under a considerable compression, so that when the wire is tensioned in addition, the said packages are 35 banded with very tight wires indeed, and thus is the efficiency of the machine greatly enhanced.

In the somewhat modified form of tensioning device illustrated in Figure 12, the construction is substantially the same as 40 that just disclosed in connection with Figure 11 except that the disk 102 is replaced by the disk 150, which is provided with the holding slots 151 in to which the bight 134 can be readily brought as illustrated, 45 in Figure 12, and said disk 150 being rigid with the clutch member 95 as illustrated in Figure 13, the placing of the bight 134 into one of the slots 151 as shown, causes said bight to be positively held and to 50 take of the rotation of said clutch member 95.

Tension will therefore continue to be imparted to said bight 134 until the clutch slips, whereupon the spring 67 will be compressed, as above described, and the twisting 55 operation brought into action, all as will be readily understood from the foregoing.

It is obvious that those skilled in the 60 art may vary the details of construction as well as the arrangement of parts without departing from the spirit of the invention, and therefore, we do not wish to be limited to the above disclosure except as 65 may be required by the claims.

What we claim is:

1. In a wire tying machine the combination of a support for the package to be wired; means for compressing said package prior to the wiring operation; and means 70 to actuate said compressing means comprising a movable member to which momentum may be imparted before said compressing means begins to function, substantially as described.

75 2. In a wire tying machine the combination of a support for the package to be wired; means for compressing said package prior to the wiring operation; and means to actuate said compression means comprising a loosely mounted movable member to which momentum may be imparted before said compressing means begins to function; and loosely mounted connections between 80 said movable member and said compressing means, substantially as described.

85 3. In a wire tying machine the combination of an adjustable support for the package to be wired; an adjustable compressing means for said package movable toward and 90 from said support; a shaft for moving said compressing means; a wheel loosely mounted on said shaft for rotating the same; and connections between said shaft and wheel 95 adapted to permit said wheel to acquire a considerable momentum before actuating said shaft, substantially as described.

100 4. In a wire tying machine the combination of an adjustable support for the package to be wired; an adjustable compressing means for said package movable toward and from said support; a shaft for moving said compressing means; a wheel loosely mounted on said shaft for rotating the same; connections between said shaft and wheel 105 adapted to permit said wheel to acquire a considerable momentum before actuating said shaft; and automatic means associated with said shaft for holding said package under compression after said wheel has 110 ceased to operate, substantially as described.

115 5. In a wire tying machine the combination of an adjustable support for the package to be wired; an adjustable compressing means for said package moveable toward and from said support; a shaft for moving said compressing means; a wheel loosely mounted on said shaft for rotating the same; connections between said shaft and wheel adapted to permit said wheel to acquire a considerable momentum before actuating 120 said shaft; automatic means associated with said shaft for holding said package under compression after said wheel has ceased to operate; and means for automatically releasing said holding means upon a reversal of the motion of said wheel, substantially as described.

125 6. In a wire tying machine the combination of a support for the package to be 130

wired; means to compress said package comprising an actuating shaft; a wheel loosely mounted on said shaft for actuating the latter; connections between said wheel and shaft; and connections adapted to positively turn said wheel in one direction and to store up power to automatically turn it in an opposite direction, substantially as described.

- 10 7. In a wire tying machine the combination of a support for the package to be wired; means to compress said package comprising a movable frame carrying a wire twisting mechanism; a guide member, and an actuating shaft; a wheel loosely mount-

ed on said shaft for actuating the latter; connections between said wheel and shaft; connections adapted to positively turn said wheel in one direction and to store up power to automatically turn it in an opposite direction; a dog for preventing a reversal of the compressive action; and means for releasing said dog upon a reversal of the motion of said wheel, substantially as described. 25

In testimony whereof we affix our signatures.

ALEC J. GERRARD.
PARVIN WRIGHT.
